Patented Apr. 23, 1968

210,834

MUSIC HOLDER FOR ATTACHMENT TO MUSICAL INSTRUMENTS

Charles T. Urban, La Grange, and John Defauw, Chicago,
Ill., assignors to American Plating and Manufacturing
Company, Chicago, Ill., a corporation of Illinois

Filed July 25, 1966, Ser. No. 3,206

Term of patent 14 years

(Cl. D33—10)

FIG. 1.

FIG. 2.

FIG. 3.

FIG. 2 is a side elevational view of the music holder of FIG. 1; and

FIG. 3 is a front elevational view of the music holder of FIG. 1.

The dominant features of our design reside in those portions shown in full lines on the drawing.

The pencil shown in dotted lines is for illustrative purposes only.

The back of the holder is of conventional configuration.

We claim:

The ornamental design for a music holder for attachment to musical instruments, substantially as shown and described.
